UNITED STATES PATENT OFFICE.

ANTHONY F. LUCAS, OF WASHINGTON, DISTRICT OF COLUMBIA.

MINING-CAISSON.

SPECIFICATION forming part of Letters Patent No. 637,137, dated November 14, 1899.

Application filed June 17, 1899. Serial No. 720,947. (No model.)

To all whom it may concern:

Be it known that I, ANTHONY F. LUCAS, of Washington city, in the District of Columbia, have invented a new and useful Improvement 5 in Mining-Caissons, of which the following is a specification.

My invention has reference to the sinking of mining shafts or caissons for bridge-piers or bridge-abutments and is designed to make 10 available the disintegrating and erosive action of a flowing body of water operating under pressure to cut down through and remove the earth until bed-rock is reached.

My invention consists in the peculiar construction and arrangement of a caisson of, say, six feet in diameter, more or less, which is made in cylindrical sections which are successively bolted one on top of the other to form a continuous tight vertical caisson, which 15 is gradually sunk to bed-rock by hydraulic action, the caisson being provided with a boring-face and with means for conducting the water thereto. The caisson is also provided with special means for extending the lower 20 section into bed-rock and securing it therein with a water-tight connection, which prevents the seeping of water back into the shaft from the earth above, and is also provided with special means for turning the entire 25 caisson to produce a boring action to facilitate its downward movement through the stiffer bodies of clay, as will be hereinafter more fully described with reference to the drawings, in which—

30 Figure 1 is a side view of the derrick-scaffolding and the caisson-sections within the same. Fig. 2 is an enlarged view in vertical section of the upper and lower portions of the caisson. Fig. 3 is a top plan view of the 35 same. Fig. 4 is a view of the underneath boring-face. Fig. 4^a is a sectional detail thereof, and Figs. 5, 6, and 7 are detail views of devices for oscillating the caisson about its vertical axis for promoting its passage through 40 the earth.

In the drawings, Fig. 1, S represents an elevated scaffolding or framework of heavy timbers, within which the caisson C is sustained and guided while being sunk into the 45 earth. For regulating its movement a series of brake-shoes s, Figs. 1 and 3, are provided

at suitable points along its sides, which are by means of set-screws s' brought to a frictional bearing against the sides of the caisson, both to retard its too-rapid descent, when 55 necessary, and to hold it in vertical alignment and guide it in its downward movement. The caisson is composed of cylindrical sections of heavy boiler-iron, provided at its edges with suitable holes for successively bolting section upon section as the caisson works 60 its way into the earth. Centrally within the caisson there is (see Fig. 2) arranged a vertical water-pipe A, which is fixed at its bottom end to the boring-face of the caisson and 65 is built up in sections from time to time. This pipe conveys to the bottom of the caisson the head of water which is employed to disintegrate and remove the earth from the downward path of the caisson. The pipes A A² are 70 connected to each other at suitable distances apart by a three-way gate having valves a a' a², of which only the two valves a' a² need be employed. The upper valve a² controls the upper opening of the gate and the valves a a' 75 the lateral opening A' A³. The flexible water-pipe P from the pump connects with the lateral opening A', and when the upper valve a² is closed and the valve a on the side is 80 closed and a' on the other side is open water 85 entering through the opening A' is delivered to the bottom of the caisson continuously and without interruption. I prefer to have the central stand-pipe A of metal and connect the flexible hose-pipe with it at the top opening 85 A', so as to avoid the bursting strain which a long vertical length of flexible pipe would have at its lower end from the head of water and internal pressure. In building up the central stand-pipe I leave the three-way gate 90 in place and merely screw (see Fig. 2) a second section A² of water-pipe into the upper opening of the gate. The gate is then a mere connection in which the openings A' A³ are closed by its valves a a', and the other valve 95 a² is open to give free passage of water from A² to A. On the top of the section A² another three-way gate is then placed and the flexible hose-pipe connected to its lateral opening in 100 the same way.

At the bottom of the caisson there is an external telescopic section C', which is tempo-

rarily bolted to caisson C and at its lower end has bolted to it a sectional driving-head or boring-face composed of four quadrantal plates B B B B. These have radial flanges 5 b b on their upper faces, that are bolted together. These sectional plates are cast hollow, with passages b' opening both peripherally outside the caisson, as seen in Fig. 2, and also centrally into the water-pipe A. At the four 10 radial joints of the quadrantal plates B there are formed thickened bearing-faces b² b² and sharp radial ribs b³. The bearing-faces b² rest on the earth and leave channel-ways between them for the water to issue beneath the 15 false bottom, while the sharp edges b³ act as cutters when the caisson is turned. The radial bearings b² and cutting edges b³ are not only opposite the joints of quadrantal plates, but at intermediate points also, as seen in 20 Fig. 4. In the center of the false bottom there is a detachable spider E at the bottom of the water-pipe A, through which the water passes. This spider is slightly conical on its lower face and forms a centralizing boring- 25 bit. As the water passes under heavy pressure down the tube A it strikes the earth underneath the false bottom and, disintegrating it, carries it outwardly. At the periphery of the caisson it meets another strongly-ener- 30 gized and unretarded stream of water, which carries the suspended earth up with it around the external walls of the caisson to the surface. This false bottom, having the divided or double-acting currents, constitutes an im- 35 portant feature of my invention. At the outer edges of the false bottom the water-passages have an upward bend, so as to give an upward trend to the currents to more effectually lift the sedimentary matter.

40 When the caisson strikes a bed of sticky clay and the latter is not disintegrated with sufficient rapidity by the unassisted action of the water alone, I provide means for turning the entire caisson with an oscillatory motion 45 about a vertical axis. For this purpose (see Figs. 2, 3, 5, 6, and 7) a metal frame H is provided with journal-boxes to receive a short shaft having rigidly attached to it a crank-handle I and a pinion i. This pinion meshes 50 with a larger gear-wheel i², having on its side a smaller gear i³, both of which are mounted on a short shaft i⁴, journaled in the framework. This shaft passes at its end through a horizontal slot g in a casting G, which is 55 curved to correspond to the caisson and is provided with a curved series of gear-teeth, (see Fig. 7,) with which the gear-wheel i³ engages. The casting G has a series of ribs e², which play in vertical grooves e of a curved 60 plate K, rigidly bolted to the side of the caisson. This plate K not only has grooves e, but has undercut grooves e', which receive headed bolts e⁴, that connect it to the casting G. With this construction when the crank I is 65 turned the gears i i² i³, acting on the teeth of casting G, turn the caisson about its vertical axis, while the vertical sliding connection

formed by the grooves e e' with the ribs and bolts of casting G allows the caisson to settle down without interference with the action of 70 the gears. When the caisson is thus turned first one way and then the other, the sharp radial edges b³ and the central, spider E cut into the refractory clay, and thus loosen it sufficiently to be carried away by the force of 75 the water.

After the shaft has been sunk through the earth to bed-rock it is necessary to tightly connect the bottom of the caisson to the bed-rock to prevent the water from flowing back 80 into the shaft at this point. For this purpose the section C of the caisson and the lowest section C' are connected together telescopic- 85 ally and are temporarily bolted together. A series of brackets D' are connected in inverted position to the caisson-section C, and another set D² are connected in upright position to the lower section C'. Screw-jacks D are placed upon the brackets D² and are made to bear against the upper brackets D'. Now when 90 bed-rock is reached the quadrantal sections B of the false bottom are unbolted one at a time and are taken out, and the bed-rock is drilled and blasted until a hole larger than the cais- 95 son is formed. Then the brackets D' D² are put in place and the jacks inserted between them and screwed up until the outer and lower section C' of the caisson is bodily forced down over the upper section C far enough to penetrate within the hole in the bed-rock and is 100 there cemented tightly in place, so that no water can enter the caisson at this point. To permit easy application of the brackets D' D², they are provided with spurs d, which are seated in holes in the walls of the caisson. 105

With regard to the function of the brake- 110 shoes s in the framework above, these in connection with a hydraulically-operated caisson have an important use, as they sustain the great weight of the caisson when it is not being rotated and prevent the caisson from settling down in the mud and occluding or closing up the lower waterways in its driving-head.

Having thus described my invention, what 115 I claim as new, and desire to secure by Letters Patent, is—

1. A caisson having at its lower end a rigidly-attached and closed driving-head made in sections, and a central water-supply pipe 120 also rigidly connected and bearing on the lower side rigidly-attached boring devices connected to and turning with the caisson about its vertical axis, substantially as described. 125

2. A caisson having at its lower end a driving-head or false bottom having channels on its outside or lower face, and also channel-ways within the same and opening peripherally, both said channel-ways opening centrally into a water-supply as described. 130

3. A caisson consisting of an outer casing, a closed lower end portion rigidly attached to the outer casing, and a rigidly-attached

central water-pipe opening through the lower end portion, said lower end portion having external channel-ways in its lower face communicating with the central water-pipe and 5 extending outwardly to the external casing substantially as and for the purpose described.

4. In a caisson, the combination of a cylindrical upper casing, a cylindrical lower casing telescoping on the upper casing and both 10 made with seat-holes near their meeting edges, brackets having spurs adapted to fit into said seat-holes in opposition to each other and jacks arranged between the brackets to force the lower section down substantially as described. 15

5. A caisson having a hydraulic driving-head closing its lower end and provided with cutting devices on its lower face, means for holding the caisson in vertical position, and 20 means for turning the whole caisson about its vertical axis substantially as described.

6. A caisson having a hydraulic driving-head at its lower end, means for holding the caisson in vertical position, and oscillating 25 devices for the caisson comprising a plate with vertical guideways rigidly attached to the caisson, a toothed and curved rack-bar having corresponding sliding guides fitting those of the rigid plate, and gear-wheels operating upon the rack-bar, whereby the caisson is turned and is allowed to settle down 30

without disconnecting or interfering with the gears substantially as described.

7. The oscillating devices for the caisson, consisting of rigid plate K with grooves e and 35 e'; the plate G with bolts, rack-teeth, and slots g; the shaft i⁴ entering slot g and having rigidly-attached gear-wheels; and means for rotating them substantially as described. 40

8. The segmental driving-head for the cais- 40 son, comprising the section B with flanges b on the upper side, bearing-faces b² and cutting edges b³ on the lower sides, and intermediate waterways b' opening peripherally substantially as and for the purpose described. 45

9. The combination with a caisson built up from sections; of a central water-tube also built up of sections and having valved connections permanently incorporated in its length of sections substantially as described. 50

10. The combination with a caisson, and its surrounding and supporting framework; of a series of brake-shoes mounted on the framework and bearing against the walls of the caisson to sustain a part of its weight and 55 prevent the too-rapid descent of the caisson, and the closure of its water-channels as described.
